UNITED STATES PATENT OFFICE.

WALTER D. TUSTEN, OF NEW YORK, N. Y.

CHAIN.

1,027,226.

Specification of Letters Patent.

Patented May 21, 1912.

Application filed January 3, 1912. Serial No. 669,295.

To all whom it may concern:

Be it known that I, WALTER D. TUSTEN, a citizen of the United States, and a resident of the city of New York, borough of Brooklyn, in the county of Kings and State of New York, have invented a new and Improved Chain, of which the following is a full, clear, and exact description.

My invention relates to an improvement 10 in chains, and particularly to the construction of the links thereof; and it has for its object to provide a novel and superior device of this kind which can be used in the making of watch chains, bracelets and other articles intended to be used for ornamental purposes.

Reference is to be had to the accompanying drawings forming a part of this specification, in which the same characters of reference indicate the same parts in all the views.

Figure 1 is a perspective view of a chain made in accordance with my invention and serving to carry a watch, the whole being 25 shown in position upon a lady's wrist; Fig. 2 is an end elevation shown on an enlarged scale, of the chain which is illustrated in position in Fig. 1; Fig. 3 is a longitudinal vertical sectional view of one of the links of the 30 chain, the plane of section being indicated by the line 3—3 on Fig. 5, and the sections of the link being shown in closed relation; Fig. 4 is a view similar to Fig. 3, showing the parts extended; and Fig. 5 is a longitudinal horizontal view taken on the curved line 5—5 of Fig. 4.

My improved chain consists of a number of links made in sections movable with respect to each other, to permit the chain to be 40 distended whenever desired, as, for instance, to permit the length of the chain to be increased when it is used in the form of a bracelet or armlet, so as to enable it to be slipped over the hand into position. The 45 links 1 are connected by means of pivots or eyelets to solid links 2, and these links may be of any desired shape or design, and may be studded with diamonds or other gems to add to the ornamental effect. The watch 50 which the chain carries is shown at 3, and this watch is of the open-face type, as indicated, and is flanked on either side by the links 2, which are arranged in alternation with the extensible links 1, over the entire 55 length of the chain, as Fig. 2 illustrates.

Each of the links 1 comprises a U-shaped

section 4, which has a pair of parallel arms 6, connected by a transverse portion 5, forming the base of the U. This section 4 is made in one piece, and is made solid, and it 60 receives between the arms 6 thereof another section 7, which is hollow, and is so connected to the U-shaped section 4 that it can be moved longitudinally with respect thereto. Viewed from the top, the sections 4 and 65 7 are straight, but viewed from the side they will be bent to conform to the wearer's arm when used in a bracelet, as shown. The sections 4 and 7 have eyelets 8 joined to their opposite ends for convenience in joining the 70 links of the chain together. As stated above, the section 7 is hollow, and it may be square or rectangular in cross-section, according to whether a broad or narrow link is desired. This section is provided with slots 9, having 75 closed ends, these slots being located in the opposite sides of the section 7, adjacent the end to which the eyelet 8 is attached; and it is also provided with a slot 10 in one of the sides, this slot being located adjacent 80 the opposite or inner end of the section 7, and being open at one end as shown. When formed in this way the section 7 will be open almost entirely on one of its sides, owing to the aligned slots 9 and 10 formed in that side, 85 but on the other side it will be closed over substantially the inner half of its length.

The numeral 11 represents a spiral spring which is housed by the section 7, one end of this spring being engaged by a pin 12 at the 90 inner end of the section, to hold the spring in place, and the other end thereof abutting against a transverse pin 13, which is mounted in the outer ends of the parallel arms 6 of the other section 4, and passes through 95 the slots 9 in the opposite side of the section 7. The pins 12 and 13 serve to compress the spring 11 when the sections of the link 1 are extended; and the pin 13 further serves to keep the outer ends of the arms 6 from 100 spreading, in addition to serving as part of the guiding means for the section by which the spring is carried.

The arm 6 of the section 4 which is located 105 adjacent the side of the section 7 in which the slot 10 is formed, is provided with a short guide pin 14. This guide pin is located adjacent the middle of the arm 6 carrying it, and its inner end extends into the slot 10, but terminates short of the turns of the spring 11. The function of this pin is 110 to prevent the section 7 from rotating around

the pin 13 as a pivot. It does not engage or interfere with the spring 11 when the sections 4 and 7 are distended; and the pins 13 and 14 by always engaging the inner section 7 at two separated points, serve to keep the sections 4 and 7 in substantial alinement when the chain is stretched.

The arms 6 of the section 4 may be broad or narrow, as desired, and may be chased or 10 worked by hand on top to give the same a suitable ornamental appearance. The section 7 will be closed on top, as shown in Fig. 3, and this part of the inner section may also be worked for the same purpose. 15 I may also mount diamonds or other gems in the tops of the arm 6 and the top of the section 7 when a jeweled chain is wanted.

From the above description it will appear that the construction of my link is both 20 strong and simple, comprising but few parts, and these parts are so made and connected together as to reduce to a minimum the liability of the link getting out of order or broken. The sections of each of the extensible links will always be held in substantial alinement with each other, owing to the arrangement of the guiding means shown; and all of the parts which permit the relative movement of the links in the manner described 25 are completely incased to prevent the same from injury.

I wish to have it understood that the drawings and description of my invention are illustrative only, and that I do not care 30 to be limited to the necessary details of the construction, except in so far as is indicated in the accompanying claims; and I also desire to have it understood that while my chain is described above as being employed 35 in connection with articles worn for ornamental purposes, it is by no means limited to such uses, as will be readily perceived.

Having thus described my invention, I 40 claim as new and desire to secure by Letters Patent:

1. An improvement in chain links, comprising a pair of extensible sections, one of said sections being substantially U-shaped, and the other of said sections being received 45 between the arms of said U-shaped section, resilient means carried by said other section, a pin carried by the outer ends of the arms of the first-named section passing through said other section and engaging 50 said resilient means to permit said sections to have relative movement, and means carried by one of the arms of said first section and extending into the second section in position to clear said resilient means, to prevent 55 one of said sections from rotating around said pin as an axis, whereby the said sections will be maintained at all times in substantial alinement.

2. An improvement in chain links, comprising a U-shaped section having parallel

arms, a second section received between said arms, resilient means carried by said second section, a transverse pin carried by the arms of the first section passing through said second section and engaging said resilient means to permit the said sections to have relative movement, and a pin carried by one of the arms of the first-named section extending into the second section, but terminating short of said spring to avoid interfering with the same, said second pin preventing the second-named section from rotating around the first pin as a pivot, whereby the said sections will be maintained at all times in substantial alinement with each other. 70

3. An improvement in chain links, comprising a U-shaped section having parallel arms, a second section received between the arms of said U-shaped section, said second section being hollow and carrying resilient means on the interior thereof, a stud or pin mounted in one end of the said second section to engage one end of said resilient means, a pin mounted in the arms of said U-shaped section and extending through 75 said second section and engaging the other end of said resilient means, whereby said sections will be secured together but will have relative movement, and guiding means carried by one of the arms of said U-shaped section and extending into the first-named section at a point remote from the pin carried by the arms, said guiding means terminating short of said resilient means to avoid interfering therewith, whereby the second section will be prevented from tilting with respect to the U-shaped section around the pin carried thereby as an axis, so as to maintain the said sections at all times in substantial alinement with each other. 80

4. An improvement in chain links, comprising a U-shaped section having parallel arms, a hollow section received between said arms, said hollow section having slots with closed ends in its opposite sides adjacent the outer extremity thereof, resilient means carried by said hollow section, said section having means to engage one end of said resilient means to hold the same against movement, a pin carried by the arms of said first section extending through the slots in the opposite sides of the second section and engaging the other end of said resilient means, whereby said sections will be secured together but will have relative movement, said hollow section having a third slot in one of its sides adjacent the inner end thereof, and guiding means carried by one of the arms of the first section and extending into said third slot, but terminating short of said resilient means to avoid interfering therewith, whereby the sections will be prevented from rotating with respect to each other around the said pin as an axis, and will be held at all times in substantial alinement with each other. 95

5. In a link of the kind described, the combination of a pair of extensible sections, means carried by one of said sections and engaging the other section, resilient means 5 engaging the other section and said first-named section to permit said sections to have relative movement, and additional means carried by the first-named section and engaging the said second section in position to clear said resilient means, to prevent

said second-named section from rotating about the first-named engaging means as a pivot.

In testimony whereof I have signed my name to this specification in the presence of 15 two subscribing witnesses.

WALTER D. TUSTEN.
